UNITED STATES PATENT OFFICE

MAGGY BESANÇON DE WAGNER, OF PARIS, FRANCE, ASSIGNOR TO LENTHERIC, INCORPORATED, OF NEW YORK, N. Y., A CORPORATION OF NEW YORK

DESIGN FOR A BOTTLE

Application filed February 25, 1930. Serial No. 34,648. Term of patent 14 years.

To all whom it may concern:

Be it known that I, MAGGY BESANÇON DE WAGNER, a citizen of France, residing at 26 Avenue du Bois, Paris, France, have invented a new, original, and ornamental Design for a Bottle, of which the following is a specification, reference being had to the accompanying drawings, forming a part thereof.

In the drawings:

I claim:

The ornamental design for a bottle substantially as shown.

MAGGY BESANÇON DE WAGNER.
